P. IBACH

SWITCH ACTUATING DEVICE

Filed June 28, 1920

Inventor:

Peter Ybach
by *Steinhardt*
Attorney.

UNITED STATES PATENT OFFICE.

PETER IBACH, OF KONIGSWINTER, GERMANY.

SWITCH-ACTUATING DEVICE.

Application filed June 28, 1920. Serial No. 392,466.

To all whom it may concern:

Be it known that I, PETER IBACH, a citizen of the German Empire, residing at Konigs-winter, Germany, have invented certain new and useful Improvements in Switch-Actuating Devices, of which the following is a specification.

My invention relates to a device for automatically starting and stopping an electro-
10 motor driving an air pump or compressor.

It is already known to open a blow-off valve and to operate the starter of the motor by means of a piston driven by the generated compressed air, as soon as a predetermined
15 pressure has been reached in the pipe leading to the compressed air duct.

My invention more particularly refers to a device of the kind aforesaid in which not only the starter for the motor, but also the
20 supply switch is cut out automatically as soon as a predetermined air pressure has been reached in the air duct, these switches being again switched on automatically after the pressure has fallen.

25 In the drawings affixed to this specification and forming part thereof a device embodying my invention is illustrated by way of example in diagram.

Referring to the drawing, 1 is the piston
30 serving for throwing the current in and out, and 15 is the cylinder, in which this piston is arranged to reciprocate and which is connected by pipes 16 and 17 with the pressure reservoir 18 of the compressor 19.
35 20 is the electromotor driving the compressor. In the pipes 16, 17 there is inserted another cylinder 21 and a weighted piston 22 is arranged to reciprocate in this cylinder.

40 On the pressure in the reservoir 18 increasing unduly the piston 22 will be raised and communication will be established between the pipes 16 and 17. On the other hand, as long as the pressure remains normal or when it drops again, after having raised the piston 22, this latter in its lowermost position will establish communication of pipe 16 with the atmosphere by way of the conduit 23 provided in the piston. 2 is a rope having one end attached to piston 1, while its other end is fixed to a sheave 3. 4 is a sheave of larger diameter coaxial with sheave 3, and 5 is another rope having one end fixed to

sheave 4 while the other end is connected to the weight 12. 11 is the contact brush of the starting switch 18, said brush being fastened to said rope. 13 is the supply switch whose lever is resting on the fork 7 of a loose sheave 6 carried by the rope 5 and having the weight 8 suspended therefrom, said weight being heavier than weight 12. 9, 10 and 12 are guide sheaves for rope 5. The double sheave 3, 4 merely serves for increasing the distance travelled by rope 5.

The operation of this device is the following: As soon as compressed air is introduced 65 into cylinder 15 by aid of pipe 16, the piston 1 is lowered and by exerting a pull on rope 2 causes rope 5 to be shortened and the lighter weight 12 to be lifted, the heavier weight 8 still resting on its basis 16. The contact 70 brush 11 is carried past the contacts of the starting switch 18 and throws the motor out. Only after the brush has reached its end position the heavier weight 8 is lifted and the supply switch 13 is thereby quickly 75 opened. Owing to the tackle-action of the sheaves only one half of the weight 8 becomes effective.

Whenever the piston 1 rises, the heavy weight 8 first closes the switch 13. Only 80 after said weight is resting again on its basis, the lighter weight 12 will carry the brush 11 past the contacts 18, thus throwing the motor in again.

I wish it to be understood that I do not desire to be limited to the exact details of construction shown and described, for obvious modifications will occur to the person skilled in the art.

I claim:

In a device of the kind described in combination, a pressure pump and an electro-motor for operating said pump, a piston adapted to be displaced by an excess pressure generated by said pump, a rope connected at one end to said piston, a weight acting on the other end of said rope, a larger weight acting on said rope intermediate its ends, a motor starter operatively connected to said rope intermediate said weights and a supply switch adapted to be influenced by said larger weight.

In testimony whereof I affix my signature.
PETER IBACH.
